UNITED STATES PATENT OFFICE.

THOMAS H. SEELEY, OF MALDEN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

CONTROLLING MECHANISM FOR TACKING-MACHINES.

1,278,233.

Specification of Letters Patent. Patented Sept. 10, 1918.

Original application filed November 8, 1915, Serial No 60,309. Divided and this application filed November 25, 1918. Serial No. 133,491.

To all whom it may concern:

Be it known that I, THOMAS H. SEELEY, a citizen of the United States, residing at Malden, in the county of Middlesex and 5 State of Massachusetts, have invented certain Improvements in Controlling Mechanisms for Tacking-Machines, of which the following description, in connection with the accompanying drawings, is a specification, 10 like reference characters on the drawings indicating like parts in the several figures.

The invention to be hereinafter described relates to lasting machines, and more particularly to that type of lasting machines 15 which is adapted to work on different portions of the upper materials successively as described in United States Patent, No. 584,744, dated June 15, 1897.

In machines of this type, devices such as 20 pincers are actuated to grip and pull or updraw the upper materials and overdraw or lay them upon the innersole, and a wiper is usually employed in connection with the pincer devices to engage the upper materials and press or wipe them smoothly upon the innersole. The upper materials are secured in lasted position by fastenings, such 25 as tacks, which are fed successively to fastening, inserting or tack driving means. 30 During the lasting and tack driving operations on this type of lasting machine, the shoe is ordinarily held in both hands of the operator while his foot maintains the starting and stopping treadle in position to continue the machine in operation.

When a shoe has been lasted and while the operator reaches for another shoe, it is expedient that the machine continue in operation, and in practice this is the usual custom. During this idle operation of the 40 machine, loss of tacks is liable to occur, because in the absence of means to prevent it, the tack-feeding means and driver remain in operation when no shoe is in the machine.

In prior machines of this type, provision has been made for suspending the operation of the tack-feeding means when a shoe is not in position for the lasting operation 45 and permit operation of the feeding means when a shoe is placed in the machine. In some of such cases the driver has remained

in operative condition, or if held in inoperative condition, it has been freed by the act of placing the work in the machine. An 55 important feature of the present invention consists in the provision of means which normally lock the tack-feeding means and the tack driver when a shoe is not presented for the lasting operation, and which is positioned by the introduction of the work for 60 unlocking the tack-feeding means and moving parts into operative relation for automatically unlocking the tack driver.

With respect to this feature of the invention, a unitary member is under the control of a work-engaging part, which serves to position the member to permit the tack-feeding means and the tack driver to be 65 automatically operated when a shoe is presented to the machine, but fails to move said member to permit such operative condition when there is no shoe in position to be lasted.

Another important feature of the invention 70 consists of a controlling member for the tack-feeding and driving means movable by the work to permit operation of the tack feeding means, and automatically 75 movable after it has been first moved by presentation of the work, to unlock the driving means.

The above features of the invention and others not hereinbefore specified, as well as certain novel constructions and combinations of parts, will now be described in connection with a machine of the type set forth in the application of Thomas H. Seeley, Serial No. 60,309, filed November 8, 1915, of which the present application is a division, but it is to be understood that the invention is not to be considered as necessarily restricted in its application to this type of machine, nor to the particular details described in making disclosure of the invention.

In the drawings:—

Figure 1 is a perspective view showing a lasting machine with the present invention applied thereto, only such parts of the 100 lasting machine being illustrated as are desirable in order to show the connection and relation of the present invention therewith:

Fig. 2 is an enlarged detail partly in sec-

tion, showing the tack driver and driver lock, and associated parts;

Fig. 3 is an enlarged perspective detail relating to the tack-saver;

5 Fig. 4 is a sectional and part elevational detail of the tack carrier slide and wiper mechanism;

10 Fig. 5 is a detail in perspective showing the relation of parts when the tack-feeding means is locked or prevented from feeding tacks; and

15 Fig. 6 is a plan view in detail showing the member for controlling the locked or unlocked condition of the tack-feeding means and tack driver.

The head frame of the machine may be of any character suitable for supporting the operating parts of the machine, and as shown, consists of the casting or otherwise 20 suitably formed frame 2 carrying the usual driving shaft 3, Fig. 2, which may be driven from any convenient source of power. The usual pincer mechanism and the operating means therefor are not herein shown as they 25 may be of any character suitable to the work to be done, or like the devices described in the application of which this is a division. After the pincer-gripping and overdrawing movements have placed the upper over the 30 innersole, or in treating certain portions of the upper materials, as about the heel for instance, the upper materials may be laid over and upon the innersole by a wiper, as well understood by those skilled in the art. 35 This wiper may be of any character suited to its purpose, but as illustrated in the present instance of the invention, the wiper is mounted for movement in an inclined path relatively to the edge of the shoe to conform to the direction of plaits that may be made by the pincer mechanism, as fully described in the United States Letters Patent to Bates, No. 1,029,840, dated June 18, 1912. While this character of wiper and its action 40 may be advantageously employed in some cases, the invention herein is not dependent upon the wiper, but such wiper may be omitted and dependence placed upon the usual tack carrier slide for wiping the upper 45 materials into lasted position, as will be readily understood.

In the present embodiment of the invention, the tack carrier slide 74 carries the tack carrier 75 having an opening 76 therethrough, for receiving a tack from the tack feeding means, as will presently be described, and presenting the tack to the driver. In operation, the slide bar is reciprocated to carry the tack carrier back and forth, and when the tack carrier reaches a suitable position in its rearward movement, a tack is transferred from a raceway into the aperture 76 of the tack carrier and then the tack carrier is moved forward into 60 proper timed relation to the operation of the

pincers, and may act to wipe the overlaid upper onto the innersole. A driver then forces the tack carried in the aperture of the tack carrier through the upper materials to secure them in lasted position.

70

Pivotaly mounted at 77, Fig. 1, on the tack carrier 75, is the wiper 78 which will partake of the reciprocating movement of the tack carrier 75; and in order that the wiper 78 may be given the inclined direction 75 already described, the rear end portion of the wiper is provided with a roll 79 which engages a U-guide 80, the position of which is under the control of an arm 81, Fig. 1, connected to the swing member 82, Fig. 1, 80 substantially as more fully explained in the patent to Bates, to which reference has been made.

The tacks or fastenings which are to secure the upper in lasted position, are supplied through a suitable raceway 85, and delivered to a tack separator 86, Fig. 3, which has a reciprocating movement across the end of the raceway to detach therefrom singly and deliver to the tack carrier, a tack to be 90 placed in position for the driver.

Reciprocating movements are imparted to the tack separator 86 by the rack and segment 87, 88, respectively, the latter being formed as part of a yielding member 89, as usual, and normally under the influence of a spring 90 against the tension of which the yielding member 89 may be appropriately moved by means of a cam 189 on the tack carrier slide and a roll 190 on the yielding 100 member 89, to effect reciprocation of the tack separator 86. In the present form of the invention, the yielding member 89 is composed of two parts, the segment carrying portion and the operating portion 91. 105 said two portions of the member 89 being substantially of the construction heretofore common in this class of devices, and the construction being such that while the tack separator 86 may be reciprocated to detach a 110 tack from the raceway and deliver it to the tack carrier when such separator movement is not obstructed, yet when there is obstruction to the tack separator movement, the two portions of the member 89 may yield to permit the tack separator to remain at rest.

115

The general construction and operation of the parts relating to the tack separator and tack supply may be as heretofore common in the art.

120

When the operator has finished lasting one shoe, he places it upon a suitable rack or receiver and reaches for another shoe. During this time he maintains his foot upon the starting treadle, with the result that the machine continues in operation. To prevent a loss of tacks, it is expedient that means be provided to interrupt the supply of tacks when there is no shoe in the machine during the operation thereof and it is likewise de-

125

130

sirable that upon presentation of the shoe to the lasting instrumentalities, the individual supply of tacks to the tack driver be permitted and that the tack driver itself be 5 free to perform its driving function. To these ends, the present invention contemplates the provision of means whereby when there is no shoe presented to the machine, the tack feeding means and the tack driver 10 shall be locked from operation, and that when a shoe is placed in the machine or presented for the lasting operation, the tack feeding means shall be unlocked and that parts be placed in operative position for 15 automatically unlocking the driver.

The shoe rest 92, Fig. 1, is secured at 93 upon an adjustable support 94 which is connected to a bracket 95 extending from the head frame. The support 94 may be appropriately connected to the bracket 95 adjustably by any suitable means, such for instance, as the clamping bolt 96, a suitable guideway 97 being employed for properly guiding the support 94 in its adjusting 20 movement. Pivotaly mounted at 98 to suitable lugs projecting from the shoe rest 92, is an auxiliary shoe rest 99, preferably one member being disposed at each side of the shoe rest 92. Pivotaly mounted upon 25 the adjustable support 94 by means of the pin 100 is the two-arm lever 101, one arm of which is connected by a link 102 to the rear end of the auxiliary rest 99, as at 103. An adjusting bolt 104 or other suitable adjusting means may be provided to limit the 30 swinging movement of the auxiliary shoe rest 99 upon its pivotal mounting 98. The other arm of the two-arm lever 101 is connected at 105 to a rod 106 which is itself 35 connected at 107 to a member 108 pivotally mounted at 109 on an arm 110 secured to the driver controlling shaft 111. A spring normally acts upon the member 108 to draw the 40 rod 106 to the right, Fig. 1, or in other words, to hold the auxiliary shoe rest 99 45 below the shoe rest 92. The spring device for performing this function may be of any usual construction, but in the present instance of the invention, it comprises the 50 spring 112 seated in a suitable recess of the arm 110 secured to the driver controlling shaft as indicated in Fig. 6, and a pin 113 engages this spring and the member 108 to normally turn the said member clockwise, 55 viewing Fig. 6, the construction being such that when the auxiliary shoe rest is not pressed upwardly by the introduction of a shoe, the parts will assume the position indicated in Figs. 1 and 6.

Extending downward from the member 60 is a pin 114 which may be suitably clamped to said member by a bolt or screw 115, Fig. 1. The pin 114, when the member 108 is under control of the spring 112, and 65 no shoe is in the machine, normally stands

as indicated in Fig. 5, in the path of movement of the tack separator slide or rack bar 116 and serves to effectively lock or prevent movement of the tack separator; but upon presenting a shoe to the machine for 70 the lasting operation, the auxiliary shoe rest 99 is turned about its pivotal mounting, thereby drawing the rod 106 to the left, Fig. 1, and turning the member 108 counterclockwise, Fig. 6, to thereby remove the pin 75 114 from the path of movement of the separator slide or rack bar 116 so that the separator or tack feeding means is then free to be operated.

Mounted upon the main shaft 3 is the tack 80 driver lifting cam 117, Fig. 2, adapted to engage the driver bar 118, and raise it against the action of the usual tack driver spring. At the lower end of the driver bar 118 is the driver 120, the end of which is 85 adapted to pass into the opening 76 of the tack carrier, when the latter has moved a tack into tack-driving position, and force the tack into the upper materials for securing them in lasted position. 90

It is a feature of the present invention that when no shoe is in the machine the tack driver be locked from performing its driving function; and to this end, the driver bar 118 is provided with a notched portion 121, Fig. 2, adapted to be engaged by the end 122 of a spring actuated locking bolt 123 mounted for movement in suitable ways 124 of a bracket secured to the head frame. The spring 125, Fig. 2, may be conveniently carried in a recess in the locking bolt 123, one end resting upon the bottom of the recess and the other end against an abutment 126. The locking bolt 123 extends outwardly and is provided with an enlarged portion 127, the shoulders 127^x of which limit the inward movement of the locking bolt, and such enlarged portion is connected to a part 128, Fig. 1, having a locking notch 129 to engage the locking shoulder 130 mounted on an arm 131 secured to the driver controlling shaft 111, the construction being such that the spring 125 normally acts to force the locking bolt 123 into locking engagement with the driver bar 118 as indicated in Fig. 2, and in such position of parts the locking shoulder 130 is in engagement with the locking recess 129. Upon rotative movement of the driver controlling shaft 111, counterclockwise, viewing Figs. 1 and 6, it will be apparent that the locking bolt 123 will be withdrawn from locking engagement with the driver rod that the driver will then be permitted to drive a tack. 110

In order to effectively unlock the driver 125 when a shoe is in position in the machine, automatic means are provided, the parts of which are operatively related when a shoe is placed in the machine. To this end the member 108 is provided with a projection 130

132, Fig. 6, which, when no shoe is presented for the lasting operation and the said member 108 is performed into the position indicated in Fig. 6 by its spring 112, 5 is not in the path of an actuator 133 which has reciprocating movement. In the present instance of the invention, the actuator 133 is formed as a finger secured by suitable means such as the bolt 134 to the tack carrier slide 74, the construction being such that when the tack carrier slide is reciprocated as hereinbefore described, the actuator 133 will move correspondingly and if a shoe has been placed in lasting position in the machine, the projection 132 on the member 108 15 will have been moved into the path of the actuator 133, thereby operatively associating the projection 132 and the actuator 133 and effecting movement of the driver controlling shaft 111 to withdraw the locking bolt 123 from engagement with the driver rod 118.

From the construction described as one convenient form or embodiment of the invention, it will be noted that when a shoe is 25 not presented to the machine, both the tack feeding means and the tack driver are locked against operative movement; but when a shoe is presented to the machine, the member 108 will be moved as hereinbefore explained, thereby unlocking the tack feeding means and rendering the automatic means operable for unlocking the tack driver, so that upon reciprocating movement of the carrier slide 74 the tack feeding means will 30 first be operated to feed a tack to the tack carrier and upon further movement of the carrier slide in the same direction the tack driver will be automatically unlocked to permit it to drive the tack presented by the 35 tack carrier.

Changes may, of course, be made in the various constructions and details of the invention as hereinbefore explained, without departing from the true scope thereof as 40 pointed out by the claims; but the described construction has been found a convenient and good, practical form of the invention.

What is claimed is:—

- 50 1. In a machine of the character described, the combination of a tack driver, a tack carrier for positioning a tack for the action of the driver, means rendered operative for feeding tacks to the tack carrier by presentation of the work, means normally acting to lock the tack driver, and means rendered effective by presentation of the work and actuated by movement of the tack carrier for unlocking the tack driver.
- 55 2. In a lasting machine, the combination of tack feeding devices, a tack carrier, a tack driver, and means for normally locking the tack feeding devices and tack driver and movable by presentation of the work 60 to unlock the tack feeding devices and a

part movable by said means into position for actuation by the tack carrier for unlocking the tack driver.

3. In a machine of the character described, the combination of tack feeding 70 devices, a tack driver, a member for preventing the operation of the tack feeding devices and tack driver, means for moving said member by presentation of the work to permit operation of the tack feeding devices, and automatic means for further moving said member to permit operation of the driver. 75

4. In a machine of the character described, the combination of tack feeding and 80 tack driving means, a member for preventing the operation of said tack feeding and tack driving means, means for manually moving said member to permit operation of the tack feeding means, and automatic means for further moving said member to permit operation of the tack driving means 85 after said member has been first manually moved.

5. In a machine of the character described, the combination of tack feeding 90 means, a tack driver, a lock for preventing operation of the tack driver, a member having a part for locking the tack feeding 95 means and movable by presentation of the work to withdraw said part from locking position, and automatic means for further moving said member to withdraw the driver lock after said member has been first moved to unlock the tack feeding means. 100

6. In a machine of the character described, the combination of tack feeding means, a tack driver, a member for preventing the operation of said tack feeding means and tack driver, means movable by the work for positioning said member to permit operation of the tack feeding means, and automatic means for giving additional movement to said member after it has been 110 first moved by presentation of the work. 110

7. In a machine of the character described, the combination of tack feeding means, a tack driver, a member mounted for swinging movement and having a part to 115 prevent operation of the tack feeding means, a rest for swinging said member by contact with the work to permit operation of the feeding means, a second part carried by said swinging member, automatic means 120 to engage said second part and move the swinging member after said member has been first moved by the work, and means connected to said swinging member for controlling the operation of the tack driver. 125

8. In a machine of the character described, the combination of tack feeding means, a tack driver, a controlling member for said feeding means and driver, automatic means for actuating said controlling member, and 130

- means movable by the work as it is presented to the machine to move said controlling member for freeing the tack feeding means and placing said member in position to be 5 further moved by said automatic means.
9. In a lasting machine, the combination of tack feeding means, a tack driver, means for normally locking said feeding means and tack driver when a shoe is not presented to the machine during its operation, a member for controlling both of said locking means, means for moving said member to one position when a shoe is presented to the machine to thereby unlock the feeding 10 means, and automatic means for further moving said member for unlocking the 15 driver.
10. In a lasting machine, the combination of tack feeding means, a tack driver, means for normally locking said feeding means and tack driver when a shoe is not presented to the machine during its operation, a member for controlling both of said locking means, means for moving said member to one position when a shoe is presented to the machine to thereby unlock the feeding 20 means, and automatic means for operating the tack feeding means and unlocking the tack driver.
11. In a machine of the character described, the combination of tack supplying mechanism including a tack feeding device, a continuously moving actuator maintaining constant connection with the tack feeding 25 device, a tack driver, and means including a part that is moved automatically when the work is withdrawn from tack receiving position to prevent the feed of tacks and the operation of the tack driver.
12. In a machine of the character de- 30
- scribed, the combination of tack feeding means, a tack driver, a controlling member for said feeding means and driver movable about a center upon presentation of the work to tack receiving position to permit a 45 tack to be fed, and automatically movable thereafter about a different center for controlling the tack driver movement.
13. In a machine of the character described, the combination of a tack driver, 50 mechanism for operating the tack driver including a cam for lifting the driver, power mechanism for operating the cam, means for locking the driver in uplifted position, power operated means for unlocking the 55 driver, and means controlled by the presentation of a shoe for causing the power to operate the unlocking means.
14. A machine of the character described having, in combination, tack supplying and 60 inserting mechanism, power-driven operating means therefor, means adapted to render said mechanism ineffective when no work is in position to be fastened, and devices controlled by presentation of the work for 65 causing the power to actuate the last-mentioned means and cause a tack to be inserted.
15. A machine of the character described having, in combination, tack supplying and 70 inserting mechanism, power-driven operating means therefor, means adapted to render said mechanism ineffective when no work is in position to be fastened, and devices controllable by the operator for causing the 75 power to actuate the last-mentioned means and cause a tack to be inserted.

In testimony whereof I have signed my name to this specification.

THOMAS H. SEELY.
